(57) **CLAIM**

I claim the ornamental design for a football window shade or covering, as shown and described.

DESCRIPTION

FIG. 1 is a front view of a football window shade or covering according to the present invention in a closed position.

FIG. 2 is a perspective view of a football window shade or covering according to the present invention in a closed position.

FIG. 3 is a side view of the football window shade or covering of FIG. 2.

FIG. 4 is a top view of the football window shade or covering of FIG. 2.

FIG. 5 is a front view of a football window shade or covering according to the present invention in an open position.

FIG. 6 is a front view of a second embodiment of a football window shade or covering according to the present invention in an open position; and,

FIG. 7 is a front view of a third embodiment of a football window shade or covering according to the present invention in an open position.

The broken lines showing of a window and a back portion of the shade are for illustrative purposes only and form no part of the claimed design. The broken lines on the front of the portion of the window shade are for illustrative purposes only and form no part of the claimed design.
